UNITED STATES PATENT OFFICE

RUPERT E. RUNDELL, OF ROCKVILLE CENTER, NEW YORK, ASSIGNOR TO AMERICAN MACHINE & FOUNDRY COMPANY, A CORPORATION OF NEW JERSEY

CORK-TIPPER FOR CIGARETTE MACHINES

Application filed March 22, 1930. Serial No. 438,192.

This invention relates to an improved tipping mechanism to be used in conjunction with continuous rod cigarette machines, its main object being to produce a device suitable for operation at high speed by means of a continuous feed of the tipping material.

With this and other objects in view, the invention consists in certain constructions and combinations which will be hereinafter fully described and then set forth in the appended claims.

The cork or other tip material strip is fed from a reel over a guide plate by two contacting rotating rollers and is cut by a revolving knife blade. The latter is clamped on a disk supported by a shaft mounted at an angle to the cork strip so that the revolving knife blade travels with the continuous running cork strip while cutting, and thereby secures a straight cut. A ledger plate fastened to an arm which receives its motion from the said shaft follows the revolving knife blade. The cut piece of cork, constituting the tip for two cigarettes, is clamped between two rotating rollers around one of which passes the paper or other wrapper material strip to be tipped, and is thereby fed lengthwise onto the continuous paper strip. The cigarette paper is led by a guide between a pair of rollers which apply paste to the paper at equal intervals by means of properly spaced peripheral projections on one of them, the said projecting surfaces engaging a paste drum before contacting with the paper. The paper, so prepared, is carried around one of the clamp rollers heretofore mentioned in such a manner that the incoming cork tips register with the paste spots on the paper strip, and, after having picked up the tip, is then led around another drum and finally passes into the cigarette machine. In passing over the last mentioned drum, the tipped paper strip lies with its cork tips against the drum surface, so as to keep the tips under pressure while the paste is drying.

The paste may be applied either to the paper by an intermittent contact device as described, or it may be applied to the cork by passing the latter over a rotating continuous

paste surface before its entrance into the tip applying clamp rollers. In the cork tipper shown in the accompanying drawing, the paste is applied to the paper.

In the accompanying drawing which forms a part of this specification and in which like characters of reference indicate the same or like parts:

Fig. 1 is a front elevation of the improved cork tipper showing the cork feed and the paper feed, and the mechanism for joining the tips to the paper strip;

Fig. 2 is a top view of the cork feed on line 2—2 of Fig. 1;

Fig. 3 is an end elevation of the paper feed on line 3—3 of Fig. 1; and

Fig. 4 is a sectional view on line 4—4 of Fig. 2 showing details of the cork cutter, its operating disk and clamp mechanism.

In carrying the invention into effect, there is provided means for applying adhesive to separated portions of cigarette wrapper material, means for continuously feeding a strip of tip material, means for cutting the strip of tip material, and means for applying the severed strips to the adhesive portions of the wrapper material. In the best constructions contemplated, the cutting means includes a rotating knife detachably secured to a disk carried by a shaft inclined to the horizontal plane and a reciprocating ledger plate cooperating with the knife and supported by a cam operated slide. In the best constructions contemplated, also, the adhesive applying means includes a transversely adjustable pivoted guide, relatively adjustable paste carrying and applying drums, and an adjustable scraper cooperating with the former. In the best constructions contemplated, also, the means for continuously feeding the tip material includes an adjustable guide and cooperating rollers for feeding the strip, and means for applying the severed strips to the adhesive portions of the wrapper material including a pivoted frame and relatively adjustable rollers carried by said frame. These various means and parts may be widely varied in construction within the scope of the claims, for the particular machine selected to illustrate the invention is but one of

many possible concrete embodiments of the same. The invention, therefore, is not to be restricted to the specific construction shown and described.

5 Referring to the drawing, the cork tipper mechanism consists of the cork feed shown in Fig. 2 and at the left in Fig. 1, and of the paper feed shown in Fig. 3 and at the right in Fig. 1. The former is driven from a jack-shaft 10, while the latter receives its motion from the main shaft 11, which, together with the jack-shaft, are parts of the cigarette machine.

10 Jack-shaft 10 carries a spiral gear 12 meshing with a spiral gear 13 mounted on shaft 14 to which is fastened a spiral gear 15 meshing with a spiral gear 16 mounted on the inclined knife drive shaft 17.

15 To shaft 17 is also fastened a spiral gear 18 meshing with a spiral gear 19 mounted on shaft 20. The latter shaft carries also a spiral gear 21 meshing with a spiral gear 22 mounted on shaft 23 which has a spiral gear 24 meshing with a spiral gear 25 on shaft 26. Shafts 23 and 26 carry the rollers 27 and 28, respectively, through which the cork is fed. Knife drive shaft 17 is supported in bearings 29 and 30 mounted in housing 31, and carries a knife disk 32 provided with lugs 33 supporting pivot 34 on which are loosely mounted clamping fingers 35 having the shape of bell crank levers and clamping with one arm the knife blade 36 to the disk 32, and engaging with the other arm a recess of clamp-bushing 37, the bore of which is threaded and engages with the threaded hub of disk 32. In turning the clamp-bushing 37, the clamp fingers 35 will clamp or release the knife blade 36, see Fig.

20 40 In order to hold the clamp fingers 35 and the knife blade 36 in any desired position, the end of shaft 17 is threaded and is provided with a lock nut 38 by which the clamp bushing 37 is locked in position.

45 Knife drive shaft 17 carries the cam disk 39 engaging with rollers 40 and 41 pivoted on studs 42 and 43 mounted on slide 44 which is supported in housing 31 and guided by plates 45. The cam disk 39 is so constructed that, when revolving, the slide 44, which is engaged through rollers 40 and 41, will receive reciprocating motion corresponding with the forward movement of the tip material and knife blade 36, and impart it to the arm 46 provided on it which carries the ledger plate 47.

50 The cork strip C, supplied from a reel, is guided into rollers 27 and 28 by guide plates 48 adjustably mounted on stud 49 supported by housing 31. After the cork leaves rollers 27 and 28, it is guided by brackets 50 mounted on housing 31.

55 The paper feed is driven from main shaft 11 carrying a spiral gear 51 meshing with a spiral gear 52 mounted on shaft 53 which is

supported in bearings 54 on frame 55. Shaft 53 carries a spiral gear 56 meshing with a spiral gear 57 on shaft 58 supported in bearings 59 of frame 55. Spiral gear 57 meshes with spiral gear 60 mounted on shaft 61, and spiral gear 60 meshes with spiral gear 62 mounted on shaft 63 which is supported in bearings of the paste pot 64 and carries the paste drum 65.

60 The paste pot 64 is provided with lugs 66 and 67 and supported, through studs 68 and 69, by frame 55. Stud 68 is provided with a clamping nut 70, while stud 69 is eccentrically mounted so as to provide adjustment for raising and lowering of the paste pot. 75 The paste pot 64 is provided with a scraping plate 71 mounted on pivot 72 carrying arm 73 having adjusting screw 74 resting on stop-lug 75 by the tension of a spring 76. A turn of the adjusting screw 74 brings the 80 scraping plate 71 closer or farther away from the paste drum 65, thereby controlling the amount of paste carried away by the latter. Shaft 61 carries the paste-applying roller 77 having equally spaced peripheral 85 projections 78, so arranged that the peripheral distance from the center of one projection to the center of the next is equal to the length of two cigarettes, the whole circumference of the roller, in the case of two projections shown, being equal to the length of four cigarettes. 90

95 On the shaft 58 is mounted a roller 79 placed at such distance from shaft 61 as to 100 press the running paper strip P into contact with the paste-carrying projections 78 of rollers 77, thereby applying paste to the strip P at the proper intervals.

105 The strip so prepared is carried around the roller 80 against which bears a companion roller 81, the said pair of rollers being so placed that the distance of their center line from the knife 36, when in cutting position, corresponds with the length of one cork tip. By this means the leading end of 110 the tip severed from the cork strip is engaged by the rollers 80 and 81 at the instant the tip is completely severed from the cork strip. Each tip at the instant it is completely severed is thus clamped between the rollers 80 and 81, and is pressed upon a paste spot on paper strip P as it is carried forward by the movement of the rollers. The paper strip P with its so attached cork tips C is carried around a drum 82 mounted on shaft 53, with 115 the cork-tip side toward the drum, so as to press the cork tips firmly to the paper strip while the paste is drying.

120 Shaft 53 carries a spiral gear 83, driving, through intermediate gear 84, a spiral gear 85 meshing with spiral gear 86. Gear 85 is mounted on stud 87 carrying the roller 81. Gear 86 is mounted on stud 88 carrying roller 80 and adjustable by means of adjusting screw 89 through which roller 80 can be 125 130

removed toward or away from roller 81. Intermediate gear 84 is mounted on stud 90 on which is swingably supported a double lever arm 91 carrying on one end the studs 87 and 88. The other end of arm 91 has a pivot 92 engaging with adjusting screw 93 which is supported by bracket 94 attached to frame 55. By turning adjusting screw 93, arm 91 swings on stud 90 and brings rollers 80 and 81 nearer to or farther from the cork feed, thereby permitting the adjustment of the length of the cork tip.

The incoming paper strip P is guided by a guide plate 95 supported by bracket 96, adjustably mounted on studs 97 and 98. Stud 97 is provided with a spring 99 and an adjusting nut 100 so as to provide lateral adjustment.

In view of the foregoing, a detailed description of the operation of the machine is deemed unnecessary, and it is therefore omitted in the interest of brevity.

What is claimed is:

1. The combination with means for applying adhesive to separated portions of a strip of cigarette wrapper material, of mechanism for continuously feeding a strip of cigarette tip material, means for cutting the strip of cigarette tip material including a reciprocating ledger plate and a knife cooperating therewith for cutting strips of tip material to be applied to the adhesive portions of the wrapper material, and means for applying the severed strips of tip material to the adhesive portions of the wrapper material.

2. The combination with means for applying adhesive to separated portions of a strip of cigarette wrapper material, of mechanism for continuously feeding a strip of cigarette tip material, means for cutting the strip of cigarette tip material including a reciprocating ledger plate and a knife cooperating therewith for cutting strips of tip material to be applied to the adhesive portions of the wrapper material, and means for applying the severed strips of tip material to the adhesive portions of the wrapper material including a plurality of relatively adjustable rollers constructed to engage the wrapper material and the forward end of the tip material.

3. The combination with means for applying adhesive to separated portions of a strip of cigarette wrapper material, of mechanism for continuously feeding a strip of cigarette tip material, means for cutting the strip of cigarette tip material including a reciprocating ledger plate and a knife cooperating therewith for cutting strips of tip material to be applied to the adhesive portions of the wrapper material, and means for applying the severed strips of tip material to the adhesive portions of the wrapper material including a pivotally mounted frame, a plurality of wrapper material feeding rollers mounted in

said frame and means for moving said frame about its pivot to adjust the rollers relatively to the tip material feeding means.

4. The combination with means for applying adhesive to separated portions of a strip of cigarette wrapper material, of mechanism for continuously feeding a strip of cigarette tip material, means for cutting the strip of cigarette tip material including a reciprocating ledger plate and a knife cooperating therewith for cutting strips of tip material to be applied to the adhesive portions of the wrapper material, and means for applying the severed strips of tip material to the adhesive portions of the wrapper material, said tip material feeding mechanism including a plurality of adjustably mounted guide plates and a plurality of cooperating feeding rollers.

5. The combination with means for applying adhesive to separated portions of a strip of cigarette wrapper material, of mechanism for continuously feeding a strip of cigarette tip material, means for cutting the strip of cigarette tip material including a reciprocating ledger plate and a knife cooperating therewith for cutting strips of tip material to be applied to the adhesive portions of the wrapper material, and means for applying the severed strips of tip material to the adhesive portions of the wrapper material, said adhesive applying mechanism including an adjustable paste pot, a paste drum mounted in said paste pot, an adjustable scraper acting on said paste drum, and a paste applying drum having a segmental raised portion adapted to receive adhesive from the paste drum and apply it to the wrapper material.

6. The combination with means for applying adhesive to separated portions of a strip of cigarette wrapper material, of mechanism for continuously feeding a strip of cigarette tip material, means for cutting the strip of cigarette tip material including a reciprocating ledger plate and a knife cooperating therewith for cutting strips of tip material to be applied to the adhesive portions of the wrapper material, and means for applying the severed strips of tip material to the adhesive portions of the wrapper material, said adhesive applying means including a pivotally mounted guide plate which is laterally adjustable on its pivot.

7. The combination with means for applying adhesive to separated portions of a strip of cigarette wrapper material, of mechanism for continuously feeding a strip of tip material, means for cutting the tip material including a reciprocating ledger plate and a knife cooperating therewith for cutting strips of tip material to be applied to the adhesive portions of the wrapper material, means for applying the severed strips of tip material to the adhesive portions of the wrapper material, and means for reciprocating

ing said ledger plate including a reciprocating cam operated slide supporting said ledger plate.

8. The combination with means for applying adhesive to separated portions of a strip of cigarette wrapper material, of mechanism for feeding a strip of tip material, means for cutting the tip material including a shaft, a disk mounted on said shaft, and a knife secured to said disk, and means for applying the severed strips of tip material to the adhesive portions of the wrapper material.

9. The combination with means for applying adhesive to separated portions of a strip of cigarette wrapper material, of mechanism for feeding a strip of tip material, means for cutting the tip material including a shaft, a disk mounted on said shaft, a knife, and pivoted means for clamping said knife to the disk, and means for applying the severed strips of tip material to the adhesive portions of the wrapper material.

10. The combination with mechanism for continuously feeding a strip of tip material, of means for cutting the tip material including a reciprocating ledger plate and a knife cooperating therewith to cut strips of tip material.

11. The combination with mechanism for continuously feeding a strip of tip material, of means for cutting the tip material including a reciprocating ledger plate and a knife cooperating therewith to cut strips of tip material, and means for reciprocating said ledger plate.

12. The combination with mechanism for continuously feeding a strip of tip material, of means for cutting the tip material including a reciprocating ledger plate and a knife cooperating therewith to cut strips of tip material, and means for reciprocating said ledger plate including a reciprocating cam operated slide supporting said ledger plate.

13. The combination with mechanism for continuously feeding a strip of tip material, of means for cutting the tip material including a reciprocating ledger plate and a knife cooperating therewith to cut strips of tip material, and means for reciprocating said ledger plate including a slide carrying said ledger plate and a cam disk actuating said slide and so shaped to impart reciprocating movement to the ledger plate corresponding to the forward movement of the tip material and knife.

14. Means for cutting a strip of cigarette tip material comprising a reciprocable ledger plate, and a continuously rotatable shear blade cooperating therewith for shearing strips of tip material to be applied to cigarette wrapper material.

15. Means for cutting a strip of cigarette tip material comprising a reciprocable ledger plate, a continuously rotatable shear blade cooperating therewith for shearing

strips of tip material, and a cam operated reciprocating slide supporting said ledger plate.

16. Means for cutting a strip of cigarette tip material comprising a shaft, a disk mounted on said shaft, and a shear blade secured to said disk.

17. Means for cutting a strip of cigarette tip material comprising a shaft, a disk mounted on said shaft, a shear blade, and pivoted means clamping said blade to the disk.

18. Means for cutting a strip of tip material comprising a shaft, a disk mounted on said shaft, a shear blade secured to said disk, a ledger plate cooperating with said blade to shear the tip material, and a cam operated reciprocating slide supporting said ledger plate.

In testimony whereof, I have signed my name to this specification.

RUPERT E. RUNDELL.
